C. F. DRAPER.
CUTTER SHARPENER.
APPLICATION FILED MAR. 9, 1918.

1,296,054.

Patented Mar. 4, 1919.

UNITED STATES PATENT OFFICE.

CHARLES F. DRAPER, OF LANCASTER, PENNSYLVANIA.

CUTTER-SHARPENER.

1,296,054.

Specification of Letters Patent.

Patented Mar. 4, 1919.

Application filed March 9, 1918. Serial No. 221,523.

To all whom it may concern:

Be it known that I, CHARLES F. DRAPER, a citizen of the United States, residing at Lancaster, in the county of Lancaster and 5 State of Pennsylvania, have invented certain new and useful Improvements in Cutter-Sharpener, of which the following is a specification, reference being had to the accompanying drawings.

10 This invention relates to means for sharpening the cutters of rotary cutter heads, and particularly to a cutter sharpener which is adapted to sharpen knives supported in the knife mounting, which forms the subject 15 matter of a separate application, Serial No. 221,522, filed by me on the 9th day of March, 1918.

The general object of this invention is to provide a sharpening device so constructed 20 that the cutting knives shall be beveled to the correct angle without the necessity of skilled labor on the part of the workman.

A further object is to provide a device of this character in which the cutting knives 25 may be shifted outward to any desired extent beyond the cap and chip breaker and then be beveled or sharpened accurately so as to project only the proper distance beyond the cap and chip breaker and have the 30 correct angle.

A further object is to provide a device of this character which is reciprocatable along the length of the cutter head.

Other objects will appear in the course of 35 the following description.

My invention is illustrated in the accompanying drawings, wherein:

Figure 1 is a sectional view of one form 40 of cutter head with my improved knife mounting thereon and showing in perspective the sharpening device therefor;

Fig. 2 is a sectional view of a cylindrical cutter showing my improved sharpener applied thereto;

Fig. 3 is a fragmentary perspective view partly in section of a jointer with the front and rear beds showing my sharpening device applied thereto;

Fig. 4 is a fragmentary sectional view of 50 a cutter head showing a modified form of means for holding the abrading member;

Fig. 5 is a fragmentary perspective view of a part of the knife sharpener showing

abrading member holding means, the view being partly in section; and

Fig. 6 is a sectional view showing means for mounting a rotatable file in the head of the sharpener.

Referring to these drawings, 10 designates a cutter head which in this instance is illustrated as of square form and the figure illustrates my improved knife mounting, which, as before stated, forms the subject matter of a separate application, mounted upon one face of the cutter head. This 15 knife mounting comprises the chip plate 11, and the cap plate 12, between which the knife or cutting blade 13 is mounted. The cap plate 12 and the plate 11 are held to each other and to the cutter head by means 20 of equidistant screws 14 or in any other suitable manner and preferably the cap plate and the chip plate are formed with a coacting groove and rib, the rib being designated 15 whereby the cap plate and 25 chip plate are held in proper relation to each other so as to support the knife 13.

For the purpose of sharpening the knife 13 and giving it correct bevel I provide the 30 sharpening device illustrated in Fig. 1 comprising a body 16, which is curved to arch over the cap plate 12 and which at its butt end is cut away as at 17 to fit upon the corner of the cap plate 12. The opposite end of the body 16 is formed with a downwardly extending lug 18 which constitutes a stop and whose under face is smooth and 35 rests upon the beveled face of the cap plate 12. Also attached to the body 16, at its extremity, is an abrading member clamping 40 means, in this case illustrated as a barrel 19, through which a certain form of abrading member 20 is disposed. This abrading member 20 is preferably of soft iron whose 45 extremity has been impregnated with carbon, diamond dust, or other suitable abrading agents. With the device as illustrated it is possible to reciprocate the body 16 back and forth over the face of the cap plate and thus grind the beveled face of 50 the knife 13 to an angle the same as that of the beveled face of the cap 12. The body 16 is about 4" long so as to secure a firm bearing upon the rear corner of the cap plate 12 and upon the face of the beveled 55 portion thereof.

It will be obvious that with this construction the stop 18 bears upon the face of the cap 12 and the abrading member only bears upon the cutter so that the cap 12 is not 5 injured by contact with the file. From time to time the knife 13 may be shifted outward as by means of drifts inserted through openings 21 in the rear end of the cap plate, and the knife 13 may be driven out to any desired extent and then the abrading member 10 will cut the knife down until the upper face of the knife is in line with the plane of the inclined face of the cap 12, thus always keeping the knife true and preventing the 15 knife projecting beyond the chip plate and beyond the cap plate more than a predetermined amount.

In Fig. 2 I illustrate a cylindrical cutter head having a knife 13^a and formed at intervals with the recesses 22 to receive the 20 knife blades. While my improved mounting may be used in connection with the cylindrical cutter head I have not illustrated it so but illustrated an ordinary knife held in 25 place within one of the recesses by means of the usual bolts. In this case the body 16 at its rear end engages over the corner of one of the recesses while the abrading member 20 engages with the beveled face of the 30 knife. The lug 18 in this case rests upon the face of the cylindrical cutter head and limits the inward movement of the file.

In Fig. 3 I show the manner in which a 35 sharpening device of the form described for Figs. 1 and 2 is adapted to be used in connection with the rotary cutter of a jointer. In this case the body 16^a of the sharpener is not curved, but is straight so as to lie upon the back bed of the sharpener, this body 16^a 40 being provided at its rear edge with a flange 23 which rests upon the rear bed of the jointer and with a transversely extending rib or flange 18^a which also rests upon the upper face of the back bed. A strip A is 45 clamped across the bed, as illustrated, and the rear edge of the body 16^a bears against the forward edge of this strip so as to guide the sharpener as it is reciprocated. The body 16^a is formed with the barrel 19^a to 50 receive the abrading member in the manner illustrated in Fig. 1, or preferably as illustrated in Fig. 6, the detailed construction illustrated in Fig. 6 being later described.

In Figs. 4 and 5 I illustrate a manner of 55 mounting a small rectangular abrading member on my improved sharpening device without the necessity of using the form of an abrading member illustrated in Figs. 1, 2, 3 and 6. In this case the body 16 of the sharpener is formed with a flange 24 on its under face, this flange having a V-shaped longitudinally extending recess upon its inner face. The extension 25 of the body 16 is slotted at 26 and attached to the outer face of the extension 60 is a spring 27 which extends down

through said recess and is formed to provide the V-shaped groove 28. This V-shaped groove and recess and the V-shaped recess on the flange 24 are adapted to engage the abrading member 29, which is formed with beveled faces on its opposite side edges. The resilience of the spring 27 urges its depending portion toward the flange 24 and thus clamps the abrading member in position. Under these circumstances, the file may be 70 shifted in the guideways formed in the flange 24 and by the recess 28 so that as the abrading member is used it may be shifted inward to bring a new surface into contact with the knife being sharpened and thus the 75 whole surface of the abrading member may be used. Of course after the abrading member has been shifted inward to bring a fresh surface against the blade 13, the worn surface of the abrading member will bear 80 against the beveled face of the cap plate 12, but inasmuch as this face of the abrading member has been worn away, it will not abrade the cap plate. The body 16 is provided with the rib 18 which bears upon the 85 cap plate and thus supports the abrading member in proper position.

In Fig. 6 I show means for mounting a rotatable abrading member in my reciprocating sharpening device so that as the 90 sharpener is reciprocated, the abrading member will rotate to thereby bring a fresh surface into contact with the cutting knife. In this case, the body 16 is formed with a head 19^a which is recessed or otherwise 100 formed to provide a relatively enlarged chamber screw-threaded as at 30 for a portion of its length and provided at its upper end with the inwardly extending flange 31. Disposed with its lower end in this chamber is a barrel 32 having a flange 33 at its 105 lower end which confronts the flange 31 and disposed between these flanges are the anti-friction rollers 34. A screw-threaded locking nut 35 engages the screw-threaded portion of the chamber and holds the flange 32 in engagement with the balls 34.

The barrel 32 is interiorly screw-threaded and engaging the screw-threads of the barrel is a disk 36 and riveted to the under face 115 of this disk, so as to be held from rotative engagement around the rivet is a cap 37 in which is inserted the outer end of an annular abrading member 38. This abrading member may be made of carborundum, 120 emery or any other suitable abrading material and with the cap has free rotation around the pivot or axis formed by the rivet. The plate 36 is formed with recesses or perforations 39, whereby a wrench may 125 be applied to rotate the disk or plate to thereby urge the file downward from time to time and the upper end of the barrel is closed by a plate 40 having screw-threaded engagement with the barrel and also formed 130

with perforations for the insertion of a wrench or key. Preferably these perforations 41 in the member 40 are disposed in line with the perforations in the disk 36 so that the two disks may be rotated together. This disk 39 constitutes a jam nut which, when turned down, prevents reverse rotation of the disk 36 and thereby holds the file set in its adjusted positions. Otherwise than this, the construction illustrated in Fig. 6 is exactly the same as that illustrated in Fig. 1.

While I have illustrated a number of different forms of my invention, these are to illustrate the fact that it may be modified in many ways without departing from the spirit of the invention and may be used in connection with various forms of cutting heads and knives. In all of these forms there is a stop limiting the downward movement of the sharpening device and in all of these forms the sharpening device is reciprocated by hand longitudinally of the cutter head to sharpen the knife. While this device is particularly adapted for use with a knife mounting including a cap plate having a beveled face, I do not wish to be limited to this, as the sharpening device might be formed with a stop engaging the cutter head itself, as in Fig. 2.

Having described my invention, what I claim is:

1. A knife sharpening device of the character described comprising a body, the body being provided with a hollow head at one end having an inwardly extending annular flange, a barrel insertible through the head and having on its under end an outwardly extending flange, balls disposed between the flanges and permitting the rotation of the barrel relative to the head, a disk having screw-threaded engagement with the barrel,

means for locking the disk in engagement with the barrel, and an annular abrading member operatively connected to the disk and disposed concentrically to the barrel. 45

2. A knife sharpening device of the character described comprising a body having a head at one end, the head being formed to provide a chamber having an overhanging flange at its upper end, a barrel rotatably 50 mounted in the head and having interior screw-threads, anti-friction devices disposed between the barrel and the head and permitting the rotation of the barrel relative to the head, and an annular abrading member adjustably mounted upon the barrel and rotatable therewith. 55

3. A knife sharpening device of the character described comprising a body having a head at one end, the head being formed to provide a chamber having overhanging flanges at its upper end and screw-threaded at its lower end, a barrel insertible through the head and having an annular flange at its lower end confronting the first named flange, anti-friction devices disposed between the flanges, a nut engaging the screw-threaded end of the head and holding the flanged end of the barrel in place, a disk having screw-threaded engagement with the interior of the barrel, a cap mounted thereon, an annular abrading member carried by the cap, and a jam nut engaging the threads of the barrel and holding the disk in adjusted position therein. 70

In testimony whereof I hereunto affix my signature in the presence of two witnesses.

CHARLES F. DRAPER.
